UNITED STATES PATENT OFFICE.

WILLIAM E. SHEPARD, OF LINCOLN, NEBRASKA.

DISPLAY-CABINET.

1,104,711.

Specification of Letters Patent. Patented July 21, 1914.

Application filed December 19, 1913. Serial No. 807,753.

To all whom it may concern:

Be it known that I, WILLIAM E. SHEPARD, a citizen of the United States, residing at Lincoln, in the county of Lancaster and 5 State of Nebraska, have invented certain new and useful Improvements in Display-Cabinets; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to new and useful improvements in display cabinets and the object in view is to produce a simple and efficient apparatus of this nature comprising 20 a casing with a hinged side and in the provision of a series of turn down holders carried thereby, means being provided for holding the same in position within the casing.

25 My invention comprises a simple and efficient device of this character having various details of construction and combinations and arrangements of parts which will be hereinafter fully described, shown in the 30 accompanying drawings and then specifically defined in the appended claims.

I illustrate my invention in the accompanying drawings, in which:

Figure 1 is a view in elevation of a cabinet net closed. Fig. 2 is a sectional view taken 35 on line 2—2 with the cabinet in a closed position. Fig. 3 is a similar view with the cabinet open. Fig. 4 is a face view of the cabinet, and Figs. 5 and 6 are detail views.

40 Reference now being had to the details of the drawings by letter, A designates a cabinet which may be of any size or shape, and a rod B passes through the opposite sides thereof and upon which the door C is pivoted 45 totally mounted, which forms a closure for one side of the casing. Curved rods, designated by letter D, are fastened to said door, parallel to each other, and a series of holder frames E upon which the articles to be displayed 50 may be attached are provided with screw eyes F upon the lower edges thereof through which said curved rods D pass. Blocks, designated by letter H, are mounted within the casing and against which the 55 door is adapted to contact when let down and forming a support therefor.

The outermost of the frames, it will be noted, has a lug K fastened thereto, held by means of a screw, and which may be adjusted to different positions, and fastened to the inner faces of the opposite ends of the casing are two spring plates N which are provided with vertical openings O therein, each of which has a shouldered portion Q near its upper end along its forward edge 60 and each plate N is bent, preferably as shown in the drawings, in order to allow the lug K to pass over said shoulder and engage the slot for the purpose of holding the frame carrying said lug in a closed position within the casing and holding the other holding frames in position. Resilient plates, designated by letter S, are fastened to the inner faces of the opposite ends of the casing and against which the opposite ends of the 70 holders E are adapted to frictionally contact to steady the same and assist in retaining them in proper position within the casing.

75 It will be noted upon the sectional view 80 through the cabinet that the rods D are not formed on the arc of a circle but are rather cam shaped and that the highest parts of the rods, when the door is opened, are so positioned that the lugs will pass by the 85 shoulders Q and into the slots O and, when the door is closed, the cam or gradually curved portions of the rods will allow the holder frames E to lower so that the lugs will engage the slots O and securely hold 90 the holder frames within the casing. Blocks, designated by letter T, project from the rear of the casing adjacent to the lower ends thereof and are provided for the purpose of forming abutments against which 95 the lower portions of the innermost of the holder frames are adapted to contact to cause the same to be held at an inclination within the casing.

100 The operation of my invention will be readily understood and is as follows:— When the cabinet door is opened, the rods D turning with the door will cause the series of holder frames to be raised so that the lugs upon the outermost of the same 105 will be lifted out of the slots O, after which the frame will be allowed to swing freely down to a horizontal position against the cover and the following holders behind the one having the lugs may be thrown down 110 to display positions, superimposed upon the one upon the door, as will be readily un-

derstood. The holder frames are returned to their normal positions and held within the casing automatically as the door is closed.

5. What I claim to be new is:—

1. A display cabinet comprising a casing, a door hinged thereto forming a closure to one side of the casing, curved rods fastened to said door, a series of display 10 frames having sliding pivotal connections with said rods, projections upon one of said frames, and means engaged by said projections as the door is closed and serving to hold the frames in locked positions within 15 the casing, as set forth.

2. A display cabinet comprising a casing, a door hinged thereto, a series of curved rods fastened to the door, display frames, screw eyes fastened to the latter and through 20 which said rods are moved as the door is closed and opened, thereby causing the frames to be raised and lowered, a lug projecting from one of said frames, slotted plates fastened to the casing and which slots 25 are engaged by said lugs to lock the frame carrying the lugs within the casing as the door is closed and released as the door opens, as set forth.

3. A display cabinet comprising a casing, 30 a door hinged thereto, a block for support-

ing the latter, curved rods fastened to the door, a series of display frames, screw eyes fastened to the lower edge thereof and through which said rods are adapted to move as the door is opened and closed, thereby 35 causing the frames to be raised and lowered accordingly, blocks against which the lower ends of the frames are adapted to contact as they are moved back into the casing, and means for automatically locking 40 and releasing the frames within the casing as the door is closed and opened, as set forth.

4. A display cabinet comprising a casing, a door hinged thereto, curved rods fastened to the door, a frame having screw eyes through which said rod is adapted to move, plates fastened to the opposite inner faces of the casing and having vertical slots, each plate being shouldered adjacent to its 50 upper end, and lugs fastened to said frame and adapted to pass into and out of said slots automatically as the door is closed and opened, as set forth.

In testimony whereof I hereunto affix my 55 signature in presence of two witnesses.

WILLIAM E. SHEPARD.

Witnesses:

F. A. CRAWFORD,
ELMER SHEPARD.
